DOOR LOCK REPAIR UNIT

Lambert L. Beery, Minneapolis, Minn.

Application May 10, 1948, Serial No. 26,029

5 Claims. (Cl. 292—1)

1

This invention relates to new and useful improvements in door locks and more particularly to an automobile door lock comprising a rotary bolt.

Door locks of the rotary bolt type are now quite extensively used in the automotive industry because they provide a very practical and safe device for retaining such doors in closed position. Rotary bolts are subject to considerable wear, and may eventually become worn to the extent that they may fail to perform their required duties. It then becomes necessary to recondition the worn lock. This usually requires detaching the entire lock from the door, which may be more or less expensive, as it entails considerable labor and makes the job a comparatively expensive one, even though the cost of the worn part which must be replaced may be of minor importance.

An object of the present invention, therefore, is to provide a simple and inexpensive repair part, including a new bolt, which may readily be applied to a worn lock without requiring the removal of the lock from the door.

A further object is to provide means whereby the worn rotary bolt of an automobile door lock may be quickly replaced by a new bolt without removing the lock from the door, and whereby the cost of substituting a new bolt becomes a very simple and inexpensive operation.

A further object of the invention resides in the specific construction of the rotary bolt, and particularly the means for supporting the new bolt, whereby the worn condition of the original bolt-supporting shaft of the lock will have no effect upon the mounting and operation of the new bolt embodied in the lock in lieu of the original worn bolt thereof.

Another object resides in the provision of a rotary bolt having an enlarged bore therein adapted to receive a bearing sleeve secured to a mounting member, which sleeve is adapted to be fitted over the worn bolt-supporting shaft of the lock to thereby support the new bolt, and said sleeve supporting member being adapted to be fitted over the usual semi-cylindrical bracket or shield of the lock to support and partially enclose the projecting portion of the bolt.

A further and more specific object is to provide a repair part for automobile door locks whereby the usual rotary bolt may be quickly and inexpensively replaced by the use of a hack saw and a screw driver and without disturbing the mounting of the lock within the door.

These and other objects of the invention and the means for their attainment will be more

2

apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

10 Figure 1 is a perspective view showing a portion of an automobile door with the usual lock embodied therein;

15 Figure 2 is a front view of the door lock detached from the door, and showing the position of the rotary bolt in the lock and the semi-cylindrical bracket or enclosing member for supporting the outer end of the bolt supporting shaft;

20 Figure 3 is a detail sectional view substantially on the line 3—3 of Figure 2, with some of the parts omitted, showing a worn bolt prior to being replaced by a new bolt;

25 Figure 4 is a view illustrating the method of removing the worn bolt from the door lock without disturbing the mounting of the lock within the door;

30 Figure 5 is a perspective view showing the new bolt to be substituted for a worn bolt;

Figure 6 is a perspective view of the supporting bracket for the new bolt;

Figure 7 is a view illustrating the method of assembling the new bolt in the door lock;

Figure 8 is a view showing the new bolt secured in position in the lock to thereby recondition the lock for further use; and

40 Figure 9 is a detail sectional view on the line 9—9 of Figure 8, to show the interlocking engagement of the new supporting bracket with the original bracket of the lock.

45 In the selected embodiment of the invention herein disclosed there is illustrated in Figure 1 a portion of an automobile door, generally designated by the numeral 2, comprising the usual door lock 3 provided with a rotary bolt 4 adapted to engage a suitable keeper, not shown, secured to the wall of the door opening.

50 The rotary bolt 4 comprises a plurality of projections 5 which engage the keeper above referred to. These projections eventually become worn to the extent that the keeper may no longer safely secure the door in its locked position. It may then become necessary to replace the worn bolt, and sometimes the keeper. The keeper is externally secured to the wall of the door opening

55

and has nothing to do with the door lock, and the keeper may therefore be repaired or replaced at any time without disturbing the mounting of the lock. The lock is mounted within the door, as shown in Figure 1, and it is therefore customary to remove the lock from the door to gain access to the interior thereof.

In the conventional rotary bolt type lock the bolt 4 is rotatably supported upon a shaft 6 having its inner end reduced to provide a terminal extension 7 received in an aperture provided in a wall 8 of the frame of the lock and having its head suitably riveted over, as shown in Figures 3 and 4, to thereby securely anchor the shaft 6 to the wall 8.

A suitable bracket 9 is secured to the face plate 11 of the lock and projects outwardly therefrom and is shaped to provide substantially a semi-cylindrical portion which encloses the lower portion of the rotary lock 4, as clearly illustrated in Figures 2 and 3. The outer end of the shaft 6 is reduced in a manner similar to the inner end thereof and is received in an aperture provided in the outer wall 12 of the bracket 9, and suitably riveted thereto, as will readily be understood by reference to Figure 3.

The bracket 9, it will be noted by reference to Figures 3 and 4, is principally located exteriorly of the lock, and has a portion 13 extending through the face plate 11 of the lock and is suitably secured to the inner surface of the face plate 11 of the lock by such means as welding, as will be understood.

An important feature of the present invention resides in the provision of means whereby the rotary bolt or star wheel of the lock may readily be replaced by a new bolt without removing the lock from the door. To repair the door lock as above stated, a new rotary bolt 14 and mounting bracket 15 are provided. The contour of the rotary bolt or part 14 corresponds to the contour of the old bolt as originally mounted in the door, but the bore 19 of the bolt is made relatively larger than the bore in the original bolt.

The mounting bracket 15, which provides the support for the new bolt 14, has one end of a sleeve 16 secured thereto which is adapted to be inserted into the bore 19 of the bolt 14, when the parts are assembled in the lock, as will readily be understood by reference to Figures 7, 8 and 9.

The mounting bracket 15 comprises an outer wall 18 and a semi-cylindrical wall 19 which are adapted to be fitted over the cylindrical wall portion 21 of the original bracket 9 of the lock, as illustrated in Figures 8 and 9.

The cylindrical wall portion 19 of the bracket 15 is shown terminating in inwardly projecting ledges or flanges 22 and 23 adapted to engage the edges 24 and 25, respectively, of the cylindrical wall portion 21 of the bracket 9 of the lock, as clearly illustrated in Figure 9, thereby to prevent the bracket 15 from relatively rotating upon the bracket 9. A suitable set screw 26 is shown received in threaded engagement with the cylindrical wall 19 of the bracket 15 and is adapted to engage the cylindrical wall 21 of the bracket 9 of the lock thereby to secure the bracket 15 in fixed position on the lock.

To recondition the worn lock or one in which the projections 5 of the rotary bolt or star wheel have become worn to the extent that the bolt will no longer serve its purpose, the mechanic simply applies a hack saw blade 27 to the outer end of the shaft 6 of the worn lock, as indicated in Figures

2 and 3, it being understood that there is usually ample room between the end of the worn bolt and the inner surface of the outer wall 12 of the bracket 9 to receive the saw blade.

By careful manipulation of the saw, the mechanic cuts through the outer end of the shaft 6, and also severs the cylindrical wall 21 of the bracket 9 adjacent to the end wall 12, whereby the end wall 12 of the bracket 9 may be detached, as illustrated in Figure 4. The worn rotary bolt 4 may then be removed from the lock through the usual opening 29 provided in the face plate 11 of the lock.

After the wall 12 has thus been severed from the bracket 9, the mechanic, with the aid of a suitable file smoothes the roughened edges of the bracket 9 of the lock and the lock is then ready to receive the new bolt or star wheel 14, and its supporting bracket 15.

To assemble the new parts 14 and 15 in the lock in lieu of the worn parts 4 and 12, the new bolt 14 is fitted onto the bearing sleeve 16 which is machined to provide a running fit for the bolt. The bolt 14 is then fitted into the lock, the worn shaft 6 of the lock being received in the bore 17 of the bearing sleeve 16, and the cylindrical wall portion 19 of the bracket 15 fitting over the corresponding wall 21 of the old bracket 9 of the lock, as shown in Figure 8. The length of the bearing sleeve 16 corresponds to the original length of the shaft 6 of the lock whereby when the new bolt 14 and its supporting bracket 15 are secured to the lock, the lock is restored to its original usefulness, provided, of course, that none of the other parts of the lock have been worn to the extent that they may require replacement.

When the outer mounting bracket 15 has been positioned, as shown in Figures 8 and 9, the set screw 26 may be tightened whereby the ledges or flanges 22 and 23 are drawn tightly into engagement with the upper edges 24 and 25 of the bracket 9, to thereby inseparably secure the parts 14 and 15 to the lock whereby they become, in effect, an integral part thereof and are not visible from the exterior of the lock as a replacement part.

From the foregoing, it will be noted that a lock comprising a rotary bolt of the type herein disclosed may readily and inexpensively be restored to its normal condition by the simple substitution of the parts 14 and 15 for the usual rotary bolt 4, in the event that the bolt and its supporting shaft 6 become worn to the extent that they no longer safely secure the door against opening.

From actual experience, I found that the operation of reconditioning a door lock in accordance with the present invention may be accomplished in a matter of minutes, as compared to the tedious and expensive job now usually required to restore a worn lock of this type to its original usefulness.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. A repair unit for reconditioning a door lock of the rotary bolt type requiring replacement of the rotary bolt and in which the rotary bolt is normally supported on a shaft having one end supported in a bracket projecting outwardly from the face of the lock and in which the outer portions of said shaft and said bracket have been removed to permit withdrawal of said rotary bolt, said repair unit comprising a replacement bracket having a wall portion adapted to fit the remaining portion of said projecting bracket and an outer wall portion extending transversely from one end of said wall portion of the replacement bracket, said transversely extending wall portion being adapted to be connected to said shaft to support the adjacent end thereof, means for connecting said replacement bracket to said remaining portion of said projecting bracket, and a replacement rotary bolt adapted to be retained in position in said lock by said outer wall portion, whereby the lock is restored to normal use.

2. A repair unit for reconditioning a door lock of the rotary bolt type of the character described in claim 1, wherein said remaining portion of the projecting bracket is of arcuate shape, said wall portion of the replacement bracket adapted to fit said remaining portion of the projecting bracket is of arcuate shape and has inturned flanges thereon for engagement over the ends of said remaining portion of the projecting bracket and wherein screw means are provided in said wall portion of the replacement bracket for engagement with said remaining portion of the projecting bracket, whereby said replacement bracket is connected to said remaining portion of said projecting bracket.

3. A repair unit for reconditioning a door lock of the rotary bolt type requiring replacement of the rotary bolt and in which the rotary bolt is normally supported on a shaft having one end supported in a bracket projecting outwardly from the face of the lock and in which outer portions of said shaft and said bracket have been removed to permit withdrawal of said rotary bolt, said repair unit comprising a replacement rotary bolt and an auxiliary bracket having one

end of a hollow shaft secured thereto adapted to fit over the remaining portion of said shaft with the replacement rotary bolt supported by said hollow shaft and wherein the auxiliary bracket of the repair unit is adapted to fit the remaining portion of the original bracket, and means for securing the auxiliary bracket to the remaining portion of the original bracket.

4. A repair unit for reconditioning a door lock 10 of the rotary bolt type of the character described in claim 3, wherein said remaining portion of the original bracket is of arcuate shape, said auxiliary bracket has a portion thereof of arcuate shape adapted to fit the remaining portion of the original bracket, and said auxiliary bracket has inturned flanges thereon for engagement over the ends of said remaining arcuate bracket portion, and wherein screw means are provided in said arcuate portion of the auxiliary bracket for engagement with said remaining portion of the projecting bracket, whereby said replacement bracket is connected to said remaining portion of said projecting bracket.

5. An article of manufacture adapted for reconditioning a door lock of the rotary bolt type 25 comprising a bracket having an arcuate wall portion and an end wall, the opposed end edges of said arcuate wall portion having inwardly projecting flanges, and a sleeve attached to said end wall on the same side thereof as said arcuate wall portion with the axis of said sleeve coinciding with the axis of said arcuate wall portion.
